J. Klein,

Permutation Lock.

No 77,623.

Patented May 5, 1868.

United States Patent Office.

JACOB KLEIN, OF WILLIAMSBURG, NEW YORK.

Letters Patent No. 77,623, dated May 5, 1868.

IMPROVEMENT IN PERMUTATION-LOCKS.

The Schedule referred to in these Letters Patent and making part of the same.

TO ALL WHOM IT MAY CONCERN:

Be it known that I, JACOB KLEIN, of Williamsburg, in the county of Kings, in the State of New York, have invented certain new and useful Devices for Changing and Holding the Combination-Guards of a Combination-Lock for Safes; and the following is a full, clear, and exact description of the same, reference being had to the accompanying drawings, making a part of this specification, in which—

Figure 1 represents a section through the inside of the lock, with the face-plate removed, showing the internal arrangement and combination of the several parts.

Figure 2 shows an edge view of the same, with the knobs for operating broken off.

Figure 3 is a representation of a section through an end view of the same.

Figure 4 shows the face of door, with knobs and index-plates for setting and operating the lock outside of the safe.

Figure 6 represents a view of the rings, with the method of clamping and holding them from being changed by any means when the safe is closed.

Figure 7 shows the bodkin used to insert in the lock to change the combination.

The small figures under 5 and 6 are the sectional edge views of those ring-plates.

The object of my invention is the production of a simple, not expensive, and most thoroughly efficient burglar-proof safe-lock for the doors of iron safes, bank-vaults, stores, &c.

My invention consists in the arrangement and combination of the several parts, and the manner of securing them in position, so that when fastened, the lock can only be opened again by a knowledge of the position in which some of the parts are left, they being adjusted on the inside, before the door is closed and locked, the adjustment displaced by the knob A, and restored again to the proper position for opening by the index-plate, which surrounds the knob, the combinations being only known to the parties in interest.

To enable others to make and use my improved burglar-proof safe-lock, I will describe it in detail, referring to the drawings, and to the letters of reference marked thereon.

The frame, or plates, of my improved combination-lock may be of any desired dimensions and required strength, and may be secured on the inside of any door, of any required thickness, or made of any suitable material, there being no vent, or key-hole, or any opening through the door but the two round holes, which are closely filled by the shafts of the knobs A and B, and are so surrounded by caps and plates as to not leave the slightest crevice in which anything can be inserted to move the bolt or blow open the safe.

The sliding bolt D, being constructed in a similar manner to those of the ordinary lock, it having a guide-bar, D', extending in towards the rear, and held in place by the guide-piece y. The bolt D having an irregular-shaped opening, H, through it, which surrounds the shaft b of the knob B, and is operated, i. e., moved out and in by the lug f', on the shaft b, by the quarter turn of the knob B from the outside of the door.

On the top edge of the bolt D is a projection, I, in which is a groove or recess, J, and into which the catch or arm d is fitted, so as to pass in when the bolt D is drawn back. The arm d, being pivoted to a fixed stud, c, extends back over the top of plates E and F, and forms a right-angle lever with the points k and l, varying in length, so as to catch in the notches j and j', in the edges of the disks or plates E and F, when the notches are both brought in position to receive them.

On the stud, c is hinged a movable ward, e, working over the shaft b of the knob B, which, by the action of a stem or lug, f, raises the points k and l of the lever d out of the notches j and j' in the plates E and F, so that the fulcrum-end of the lever catches in the notch o in the bolt, and holds it firmly fixed, when the combination is disarranged by turning the knob A in either direction, and the bolt D cannot be moved until the combination is restored, by bringing the plates E and F again to the same position they were in when the bolt was thrown out. This is not easily effected, and can rarely, if ever, be done unless there is a knowledge of the position the plates are in when the bolt is shoved and the lever set, as seen in red lines in fig. 1.

The mechanism by which the safety of the lock is rendered so efficient is of a very simple and cheap character. It consists of a double spring, P P, (fig. 6,) secured to the disk N. The ends of the spring pressing on two reverse

keys, q q' , so as to force the keys hard in both directions against the periphery of the ring-plate M , thus forming a brake, when the ring is set to any desired or given number to form the secret combination for locking. This device is operated, and the ring-plate M released for changing the numbers, by simply inserting the oval bodkin U into the small hole g in the lock, when the hole g is in position corresponding with the opening through the lock-plate made for the purpose, thereby securing the safety and certainty of being able to open the lock when in the secret. The disk C , and the index-plate G , which is attached to the knob A , is the regulator, and the only means by which the combinations are fixed, the numbers kept registered, or retained in the memory, so that the lock can be opened by the parties in interest, and no others.

The operation of locking is as follows: The catch or arm d being in the position shown in fig. 1, the knob B is turned, and the bolt D slides out. The knob A and index G being turned in a direction from the bolt, the disk F , to which it is attached on the knob-shaft a , turns with it, and the catch b , on the lever-arm d , being lifted out of the notch j by the action of the movable ward e e , the opposite end of the lever being depressed, forms the catch o , which prevents the return of the bolt D . In the rear of the disk F is a larger plate-disk, E , which is provided with a corresponding notch, j' , in which the point k , on the lever-arm d , also catches when the two notches j and j' , in the disks E and F , come together, (as shown in figs. 1 and 3.) When the notches in the two disks thus coincide, the arm d takes the position shown in the figure, and enables the bolt D to slide out and in freely, the knob A , index G , shaft a , and disk F being connected to turn together, so that when the notch is up, and the number, say 15, coincides with the arrow-point z , or notch in the ring e , outside of the index, (as seen in fig. 4,) that number forms the base or unit of the combination.

The knob-shaft a passes through the ring-plate M , to which the disk E is fitted, and held by the brake-keys q q' and springs P P , as seen in fig. 6.

When it is desired to change the combination of the numbers, I insert the bodkin U in the hole g , and turn it one-fourth round, and the ring-plate M will be free to be moved, and the number changed to any point. Then withdraw the bodkin, and the numbers of the combination for locking and unlocking are permanently set for the time being, the number being kept where the index is at the time the bodkin is withdrawn, will be to combine with any fixed number to withdraw the bolt.

What I claim as my invention, and desire to secure by Letters Patent, is—

1. The oscillating hinged ward e e , as constructed, in combination with the catch or arm d , operating with the disks E F and bolt D , by means of the acute-angle lugs f f' , on the shaft of the knob B , substantially as herein described.
2. I claim the double-acting spring P P , the brake-keys q q' , operating reversely against the ring-plate M , for holding it in position, when set to a given number, as set forth.

In testimony wherof, I hereunto subscribe my name in the presence of—

JACOB KLEIN.
